UNITED STATES PATENT OFFICE.

WILLIAM A. TAYLOR AND COLUMBUS M. GIDLEY, OF BORGER, TEXAS.

TANK-CAR PLACARD.

Application filed November 3, 1927. Serial No. 230,824.

This invention relates to placard supports used on tank cars containing inflammable products, such placards being required by the Interstate Commerce Commission, and the general object of the invention is to provide a placard support so constructed that a placard denoting that a tank is empty may be elevated to a display position and locked in this display position, or said placard may be obscured by another placard raised to display position and locked in this position which denotes that the tank contains inflammable material and that lights and fires must be kept away, etc.

A further object is to provide a device of this character which may be readily attached to any and all tank cars, which will be durable and efficient in service, and convenient to operate, doing away entirely with the present system of tacking placards to a placard support, which placards are liable to be torn away when the car still contains inflammable material or left on the car after the inflammable material has been withdrawn from the car.

Other objects have to do with the details of construction and arrangement of parts as will appear more fully hereinafter.

Our invention is illustrated in the accompanying drawing, wherein:

Figure 1 is an elevation of a placard support constructed in accordance with our invention and displaying an empty tank placard;

Figure 2 is a vertical sectional view of the structure shown in Figure 1;

Figure 3 is a like view to Figure 1 but showing the full tank placard raised to a display position and locked in this position;

Figure 4 is a side elevation of the structure shown in Figure 3;

Figure 5 is a detail view of the means for shifting the spring tongue into its locking position and holding it in this locked position;

Referring to these drawings, 10 designates generally a bracket having a horizontal portion 11 provided with apertures 12 whereby screws may be passed through the bracket to attach the bracket 10 to the tank car at any convenient position thereon.

The bracket 10 has a vertically extending portion 13 depending from the portion 11, a horizontal portion 14 extending from the lower end of the portion 13, and then a vertically extending portion 15 extending up-

ward above the horizontal portion 11. The portion 14 of the bracket 10 is provided with a bushing 16 extending through the portion 14 and held in place by a nut 17. 60 This bushing is provided with the diametrically disposed apertures 18. Sliding through the bushing is a tubular standard 19 formed with a longitudinally extending slot 20 near its lower end and with an 65 aperture 21 disposed diametrically across from the slot but adjacent the lower end thereof.

Mounted upon the inner face of the portion 13 of the bracket is a shield plate 22 70 which, as shown, is square in shape, disposed with two corners of the plate in vertical alignment, this plate being riveted or otherwise attached to the bracket 10 and extending above this bracket, as shown in Figure 75 2. Carried upon the slideable standard 19 is a placard plate 23 which has the same form and area as the plate 22 and is disposed with two of its corners in vertical alignment. The two upper sides of this 80 plate are provided with a protecting flange 24 which projects toward the bracket 10. Mounted upon the upwardly extending arm 15 of the bracket 10 is a placard plate 25 which has the same area as the plate 23 85 and is arranged in the same relation, this placard plate being displayed when the placard plate 23 is lowered and obscured when the placard plate 23 is raised.

For the purpose of locking the placard plate 23 either in its lowered or its raised position, we provide a leaf spring 26 formed to provide a tongue 27 extending down below the lower end of the bracket 10, this leaf spring having preferably a rounded outer 95 face and carrying a locking pin 28, which is adapted to pass through the holes 18 in the bushing 16 and through the slot 20 or through the aperture 21. When this pin is pulled out, the standard 19 may be shifted 100 upward to the position shown in Figure 4 and locked in this position, as illustrated in this figure, and when the pin is pulled out from the opening 21, the standard will drop, carrying with it the placard plate 23, and 105 this placard plate will thus be lowered to the position shown in Figure 2.

For the purpose of locking the tongue 27 in its locking position or releasing the tongue so as to permit it to spring outward, we 110 provide a pin 29 carrying upon it the hasp 30. When this hasp is turned downward, as

shown in Figures 2 and 4, the spring tongue 27 will be crowded over by the hasp camming against the rounded face of the tongue 27, thus locking the pin 28 from any retraction. When this hasp 30 is turned upward, however, it will release the locking pin and the locking tongue may be manually pulled out to withdraw the pin entirely from the aperture 21, permitting the standard to be raised or lowered. This locking tongue is slotted for the reception of a sealing wire 31 or for any other suitable lock device which will hold the tongue from being shifted to release the placard standard unauthorizedly.

It will be seen that when the standard 19 is lowered, as shown in Figure 2, that the placard 23 is concealed behind the placard 22 and the placard 25 is displayed. This placard 25 preferably has upon it words indicating that the tank is empty, that it contained inflammable liquid, and warning operatives from entering the tank with exposed flame until the car has been ventilated, etc. The placard 23 carries upon it the notification that the contents of the tank are inflammable, that lights and fires must be kept away, and that the car must be handled carefully, etc. These directions are those which are required by the Interstate Commerce Commission to be applied on the placards of tank cars. These placard plates 23 and 25 will have the notice before mentioned painted upon them permanently and thus the car may be placarded either one way or the other and these placards easily and readily changed mechanically as the occasion demands without the additional relatively heavy expense of actually making a physical change of the placard itself.

As shown in Figure 5, the member 29 is formed with a spirally disposed groove 29^a and the tongue or hasp 30 has an ear 30^a bent over so as to form a hinge, which hinge engages the portion of the member 29 within the slot 29^a. As the member 30 is turned downward, the spiral slot 29^a will crowd the member 30 laterally toward the tongue 27. As it is turned upward it will move away from the tongue 27. The harder the member 30 is pressed downward, the tighter it will bear against the member 27. When the member 30 is raised manually it permits the operator to manually pull out member 27, thereby permitting the placard face to be either raised or lowered. The seal to be used with the hasp 30 is an ordinary car seal, the wire of which is passed around the bushings 16 and under member 28 and then up through the slot 30.

This device will facilitate the labeling or placarding of tank cars transporting inflammable products, is durable, efficient and economical, and complies in every respect with the requirements of the law.

We claim:—

1. A placard supporting device for tank cars comprising a bracket, a shield mounted upon the bracket, a placard mounted upon the bracket above the shield and unobscured thereby, and a placard mounted upon the bracket for sliding movement from a position behind the shield to a position in front of and obscuring the second named placard.

2. A placard supporting device for tank cars comprising a bracket having a depending portion, a horizontal portion at the lower end of the depending portion and an upwardly extending portion rising from the horizontal portion and extending above the first named depending portion and carrying a placard, a shield mounted upon the depending portion of the bracket and having an area equal to that of the placard but being disposed entirely below the same, a second placard slidably supported upon the horizontal portion of the bracket and adapted when lowered to be obscured by said shield and when raised to obscure the first named placard, and means for holding the second named placard in its raised position.

3. A placard supporting device for tank cars comprising a bracket having a depending portion, a horizontal portion at the lower end of the depending portion and an upwardly extending portion rising from the horizontal portion and extending above the first named depending portion and carrying a placard, a shield mounted upon the depending portion of the bracket and having an area equal to that of the placard but being disposed entirely below the same, a second placard slidably supported upon the horizontal portion of the bracket and adapted when lowered to be obscured by said shield and when raised to obscure the first named placard, means for holding the second named placard in its raised position, and means for locking the holding means.

4. A placard supporting device for tank cars comprising a bracket having a shield and having a supporting member extending above the shield and supporting a placard, a standard slidably mounted in the bracket for vertical movement, a second placard supported upon said standard at its upper end, the second placard when raised by a vertical movement of the standard obscuring the first named placard and when lowered by a lowering movement of the standard being obscured by said shield, and means for locking the standard in its raised position.

5. A placard supporting device for tank cars comprising an approximately U-shaped bracket, one leg of the U-shaped bracket having a horizontal attaching portion, the other leg being extended above the horizontal portion, a shield attached to the first

- named leg of the bracket, a bushing extending through the lower end of the bracket and having opposed perforations, a placard attached to the upper end of the second 5 named leg of the bracket above said shield, a standard passing through said bushing and slideable vertically therein, a second placard mounted upon the upper end of said standard and obscured by the shield 10 when the standard is lowered and when raised into a display position obscuring the first named placard, and means for locking the tubular standard in a raised position.
6. A placard supporting device for tank 15 cars comprising an approximately U-shaped bracket, one leg of the U-shaped bracket having a horizontal attaching portion, the other leg being extended above the horizontal portion, a shield attached to the first 20 named leg of the bracket, a bushing extending through the lower end of the bracket and having opposed perforations, a placard mounted upon the upper end of said standard and obscured by the shield when the standard is lowered and when raised 25 into a display position obscuring the first named placard, means for locking the tubular standard in a raised position including a spring having a tongue, a pin carried by the tongue and adapted to pass through the perforations in the bushing, the standard having a slot through which the pin 30 passes, and an aperture at the lower end of the standard through which the pin passes when the standard is fully raised.
7. A placard supporting device for tank 40 cars comprising an approximately U-shaped bracket, one leg of the U-shaped bracket having a horizontal attaching portion, the other leg being extended above the horizontal portion, a shield attached to the first 45 named leg of the bracket, a bushing extending through the lower end of the bracket and having opposed perforations, a placard attached to the upper end of the second 50 named leg of the bracket above said shield, a standard passing through said bushing and slideable vertically therein, a second placard mounted upon the upper end of said standard and obscured by the shield when the standard is lowered and when raised 55 into a display position obscuring the first named placard, means for locking the tubular standard in a raised position including a spring having a tongue, a pin carried by the tongue and adapted to pass through the perforations in the bushing, the standard having a slot through which the pin 60 passes, an aperture at the lower end of the standard through which the pin passes when the standard is fully raised, the spring acting to shift the pin outward, and means adapted to force the tongue of the spring inward and lock it in this position.

In testimony whereof we hereunto affix our signatures.

WILLIAM A. TAYLOR.
COLUMBUS M. GIDLEY.
